(57) **CLAIM**

We claim the ornamental design for protective cap for pipe, as shown and described.

DESCRIPTION

FIG. 1 is a perspective view of the protective cap for pipe, showing our new, original and ornamental design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the protective cap for pipe that form no part of the claim.
